UNITED STATES PATENT OFFICE

STANISLAUS RUSCKOWSKI, OF LOS ANGELES, CALIFORNIA

DESIGN FOR A TOWER BRIDGE

Application filed August 11, 1931. Serial No. 40,817. Term of patent 7 years.

To all whom it may concern:

Be it known that I, STANISLAUS RUSCKOWSKI, a citizen of the United States, residing at Los Angeles, in the county of Los Angeles and State of California, have invented a new, original, and ornamental Design for a Tower Bridge, of which the following is a specification, reference being had to the accompanying drawing, forming a part thereof.

In the accompanying drawing Fig. 1 is a diagrammatic top plan view of a tower bridge

showing my new design. Fig. 2 is a perspective view of a fragmentary part of the bridge with certain parts thereof broken away for convenience of illustration.

The design claimed covers a complete and definite article of manufacture which comprises an ornamental bridge and tower.

I claim:

The ornamental design for a tower bridge as shown and described.

STANISLAUS RUSCKOWSKI.
